VERY HIGH FREQUENCY LOUD-SPEAKER HORN

Robert C. Avedon, Northbrook, Ill., assignor to Electro-Voice, Incorporated, Buchanan, Mich., a corporation of Indiana

Application June 21, 1957, Serial No. 46,686

Term of patent 14 years

(Cl. D26—14)

Fig. 4.

Fig. 6.

Fig. 5.

Fig. 7.

Figure 1 is a perspective view showing my design for a very high frequency loud-speaker horn;

Figure 2 is a front view thereof;

Figure 3 is a side view thereof;

Figure 4 is a rear view thereof;

Figure 5 is a top view thereof;

Figure 6 is a cross section view as seen in the direction of the arrows along the line 6—6 of Figures 2; and

Figure 7 is a cross-section view as seen in the direction of the arrows along the line 7—7 of Figure 2.

I claim:

The ornamental design for a very high frequency loud-speaker horn, as shown.
